CLAIM

The ornamental design for a towel dispenser, substantially as shown and described.

DESCRIPTION

FIG. 1 is a front, raised perspective view of a towel dispenser according to the invention;

FIG. 2 is a front view of the towel dispenser of FIG. 1;

FIG. 3 is a rear view of the towel dispenser of FIG. 1;

FIG. 4 is a right side view of the towel dispenser of FIG. 1;

FIG. 5 is a left side view of the towel dispenser of FIG. 1;

FIG. 6 is a top view of the towel dispenser of FIG. 1; and,

FIG. 7 is a bottom view of the towel dispenser of FIG. 1.

The broken-lines shown on the surface of the drawings show portions of the towel dispenser that form no part of the claimed design. The boundary lines shown in the drawings represent boundaries of the claimed design.

1 Claim, 7 Drawing Sheets
